United States Patent Office

Des. 228,117
Patented Aug. 14, 1973

228,117

SKI ROPE HOLDER

Ronald P. Turner, Southfield, Mich, assignor to Master Industries, Inc., Ansonia, Ohio

Filed May 30, 1972, Ser. No. 258,238

Term of patent 14 years

Int. Cls. D8—08, D22—05, D8—06
U.S. Cl. D8—158

FIG. 4

FIG. 1

FIG. 2

FIG. 3

FIG. 1 is a plan view of the ski rope holder embodying my new design.

FIG. 2 is a side view thereof.

FIG. 3 is an end view taken from either end.

FIG. 4 is a sectional view on line 4—4 of FIG. 1.

I claim:

The ornamental design of a ski rope holder, as shown and described.
